UNITED STATES PATENT OFFICE

155,233

DESIGN FOR A BUTT GAUGE

William A. Priebe, Los Angeles, Calif.

Application September 23, 1946, Serial No. 133,507

Term of patent 14 years

(Cl. D52—1)

To all whom it may concern:

Be it known that I, William A. Priebe, a citizen of the United States of America, residing in the city of Los Angeles, in the county of Los Angeles, State of California, have invented a new, original, and ornamental Design for a Butt Gauge, of which the following is a specification, reference being had to the accompanying drawing, forming a part thereof.

Figure 1 is a perspective view of a butt gauge, showing my new design;

Figure 2 is a bottom view in perspective of the gauge; and

Figure 3 is a perspective view similar to Figure 2 with the gauge in reverse position.

I claim:

The ornamental design for a butt gauge, substantially as shown.

WILLIAM A. PRIEBE.
